No 983.

Design for a Door of a Cooking Stove.
by N. J. Wedder & Wm. L. Sanderson, of Troy, N.Y.:—
Assigned to L. Potter & Co., of the same place.

Patented Jan'y. 12. 1858.

Dec. 983

N. S. Vedder & Wm L. Sanderson, of Troy N.Y.

Assignors to

L. Patter & Co. of Troy aforesaid
Letters Patent No. 983 - dated Jan 12th 1858.

The schedule referred to in these Letters Patent & making part of the same.

To all whom it may concern:

Be it known that we N. S. Vedder and
Wm L. Sanderson, each of the city of Troy, in the County of Rensselaer
and State of New York, have jointly invented or produced a new and

original Design for a Door of a Cooking Stove; and we do hereby declare that the following is a full and exact description of the same reference being had to the annexed photographic drawing making a part of this specification.

Our ornamental design for a door of a cooking stove consists of the four sheets of drapery, a, a, a, a, disposed upon the four quarters of the plate, - the innermost corners of all the sheets, being twisted and turned inward toward the several centers of the sheets, thereby disclosing a raised center-piece consisting of the interior smooth convex segment, b, surrounded by the molding c, rising through the check-work ground d, which latter is enclosed by the combined scroll-leaves, e, e, e, e, f, f, f, f, and g, g, - all as shown in the drawing. -

What we claim as our invention or production, and desire to secure by Letters Patent is the ornamental design, here in described and represented in the annexed photographic drawing, for a door of a cooking stove.
